UNITED STATES PATENT OFFICE.

ADELMER M. BATES, OF CHICAGO, ILLINOIS, ASSIGNOR TO BATES VALVE BAG COMPANY, OF CHICAGO, ILLINOIS, A CORPORATION OF WEST VIRGINIA.

VALVE-BAG.

1,205,146.

Specification of Letters Patent. Patented Nov. 21, 1916.

Application filed May 17, 1915. Serial No. 28,544.

To all whom it may concern:

Be it known that I, ADELMER M. BATES, a citizen of the United States, residing at Chicago, in the county of Cook and State 5 of Illinois, have invented a certain new and useful Improvement in Valve-Bags, of which the following is a specification.

My invention relates to valve bags provided with handles, and has for its object 10 to provide such a valved bag with a handle so that it may be manipulated at all times, and particularly after the bag has been filled.

It is illustrated in the accompanying 15 drawings wherein—

Figure 1 is a side elevation of a valve bag with the handle shown partly in dotted lines and the bag collapsed. Fig. 2 is an edge view of the collapsed bag with the valve 20 distended for the admission of the filling tube. Fig. 3 is a cross section on the line 3—3 of Fig. 1 with the valve distended and the filling tube inserted.

Like parts are indicated by the same letter in all the figures.

A, A, are the sides of the bag.

B is the valve opening.

C is the bottom of the bag which is normally folded flat against the side of the bag, 30 and when the bag is hung up for filling, will appear in the position indicated in Fig. 2.

D is the top of the bag secured at one end to the fabric of the bag, but at the other 35 disconnected therefrom so as to make the valve opening B. This opening is protected or valved by the interior flap of material indicated at E in Fig. 1.

F is an inside handle member preferably 40 consisting of a flat surfaced strip placed longitudinally and parallel with the axis of the valve opening and a little at one side of the middle line of the top of the bag, and against the inner surface of the top of 45 the bag.

G is the exterior handle portion, which in this case is shown as made of heavy 50 twine, applied so as to form a closed loop, its two ends overlapped at G¹ and secured 55 from without the bag to the inner handle member by means of the staples G², G³. The valve elements may be made of any desired material, and of course, the handle may be applied to any kind of a bag, or 60 bag of any kind of material.

I have illustrated the invention here in connection with the use of a paper cement bag with satchel ends, one open to form the valve, and with a handle consisting of an interior wooden member and an exterior 60 twine member, the two secured together by staples which pass through the fabric of the bag.

The handle must be inserted through the valve opening, and since the filling tube J 65 must also be inserted through the opening, the arrangement must be such that the inner handle portion will be at one side of the filling tube axis, so that the tube or the stream of material can pass the inner handle 70 portion and not be obstructed thereby.

The use and operation of my invention are as follows:—When the valve bag is completed, that is, closed at one end and provided with a small filling tube at the other 75 end, the handle is applied by inserting the inner handle member through the valved opening, and preferably at one side thereof, and bringing it into proper position on an interior anvil which carries it and by which 80 it is inserted in the bag. The exterior handle portion is then placed in proper position, and the two are united by staples, one for each end of the inner handle portion to give length to the loop and width to the grip on 85 the bag, and another through the overlapped portions of the twine, and preferably near the middle of the inner member.

The essential features of this particular form of handle are as follows: An extended 90 inner handle member is applied to the inside of the heavy end portion of the bag, being passed in through the valve opening and placed preferably at one side of the same or away from the center of the opening so as to 95 leave room for the filling tube to slip past the inner handle portion. The handle comprises a loose, soft flexible member outside of the bag, which therefore assumes any desired position, and permits the bags to be 100 folded or laid one on another without injury to either.

It will be understood that the usual type of filling tube such as used to fill a bag of this kind is more or less pointed or sloped 105 at the forward end, being cut under ordinary circumstances something like the quill of the old fashioned quill pen. It is necessary, therefore, to have the block only slightly to one side so that it will not catch 110

on the center of the tube. If it is one side at all, the tube rides past it and no harm is done and there is no interference by the block of either the tube or the feeding stream.

I claim:

1. A handled bag consisting of a bag closed at both ends, but provided with a valve opening at one corner of one end, and 10 a handle comprising a longitudinally extended inner portion in line with but at one side of the axis of the valve opening, a flexible exterior portion, and staples whereby the two portions are secured together through 15 the fabric of the bag.

2. A handled bag consisting of a bag closed at both ends but provided with a valve opening at one corner of one end, and a handle comprising a longitudinally extended inner portion in line with but at one 20 side of the axis of the valve opening, a flexible exterior portion in the form of a loop

whose ends lie parallel with the inner portion, and staples which pass through the fabric of the bag and secure the inner and 25 outer handle portions together.

3. A bag provided with a valve opening, a handle substantially in line with said opening and parallel with the valve, a rigid interior portion located within the valve in 30 line with said opening and parallel with the handle and extending through the entire length of the handle and means passing through the wall of the bag adjacent with the end of such rigid portion and the handle 35 to hold them together.

In testimony whereof I affix my signature in the presence of two witnesses this 14th day of May, 1915.

ADELMER M. BATES.
